13 Claims. (Cl. 246—3)

1

Our invention relates to railway signaling apparatus and particularly to improved means for governing movement of traffic in track stretches by centralized traffic control.

Track stretches governed by C. T. C. from a remote control office are frequently equipped with wayside apparatus comprising a system of reversible circuits governed by traffic conditions in the stretch, while the system of circuits for each stretch is manually controlled from the office so as to at times prepare the stretch for traffic in one direction and to at other times prepare the stretch for traffic in the other direction. These circuits govern the wayside signals which control movement of traffic into and through the stretch and also control the transmission of indications to the office to show whether or not the stretch has been prepared for traffic in the desired direction and to also indicate occupancy of the stretch.

In some C. T. C. installations traffic locking circuits are provided in the C. T. C. machine to prevent interference with traffic in a stretch unless conditions are proper. These traffic locking circuits are governed by the indications received from the field stations at the ends of each stretch, and in order to insure proper functioning of the traffic locking circuits, it is essential after a change in the direction of traffic in a stretch that indications be transmitted to the office to show that the stretch has been prepared for traffic.

The indication codes sent from a field station to the office may be delayed because of the use of the C. T. C. line circuit by control codes or by indication codes from other field stations, and after a stretch has been prepared for traffic a train may enter the stretch before an indication can be sent to the office to show that the stretch has been prepared for traffic in the designated direction. The systems heretofore available have operated so that occupancy of the stretch prevents the block clear indication from being sent to the office so that under these conditions the traffic locking circuits in the C. T. C. machine may not function as intended to cause the wayside equipment to maintain the established direction of traffic in a stretch during occupancy of the stretch.

An object of this invention is to provide means for insuring that after establishment of traffic in a stretch an indication of this fact is certain to be transmitted to the office even though a train enters the stretch before the indication is transmitted to the office.

Another object of the invention is to provide block indication means which is arranged so that the means which insures transmission of indications of occupancy of the detector section at the end of a stretch also insures transmission of block clear indications.

A further object of the invention is to provide improved indication means arranged so that at each field station a single relay serves to insure transmission of indications of the occupied condition of a detector section and of the unoccupied condition of a track stretch.

Another object of the invention is to provide improved means for insuring that the traffic locking circuits in a C. T. C. machine will be effective regardless of delays in the transmission of indications from the field stations to the office.

A further object of the invention is to provide improved means for controlling the block indication lamp in a C. T. C. machine so as to prevent lighting of this lamp because of changes in either the office or the wayside equipment incident to a change in the direction of traffic in the track stretch with which the lamp is associated, but to insure lighting of this lamp during occupancy of the stretch.

Other objects of the invention and features of novelty will be apparent from the following description taken in connection with the accompanying drawings.

We shall describe one form of railway signaling apparatus embodying our invention and shall then point out the novel features thereof in claims.

In practicing our invention we provide at each end of the stretch a block indication relay having a pick-up circuit governed by the wayside signal apparatus so as to be picked up when the stretch is prepared for traffic and is unoccupied. When an end of the stretch is conditioned to be the entrance end, a stick circuit is provided for the block indication relay at that end of the stretch to keep the relay energized during occupancy of the associated detector track section, or during release of the indication stick relay for the detector section track relay, to thereby insure that once the block indication relay at the entrance end of a stretch is picked up it will not be released following entrance of a train into the stretch until an indication code has been sent to the office showing that this indication relay is picked up. The equipment at the office includes indication relays governed from the field stations at the ends of the stretch, and also includes a stick relay which is picked up when a change in

the designated traffic direction in a stretch is initiated, while this relay remains picked up until indications are received that the new direction of traffic has been established. The stick relay at the office controls traffic locking circuits in the C. T. C. machine to maintain the operator's control of traffic until a new direction of traffic is established, and as the equipment in the field is arranged to insure that, when the wayside equipment establishes traffic in the stretch, an indication of this fact will be transmitted to the office, the stick relay at the office is certain to release and discontinue its control of the traffic locking circuits so that these are thereafter subject to traffic conditions in the stretch.

In addition, the stick relay at the office, when picked up, interrupts the circuits governed by the block indication relays for lighting the block indication lamp to thereby prevent lighting of this lamp as a result of changes in either the C. T. C. machine apparatus or the wayside apparatus incident to a change in the direction of traffic in a stretch. This stick relay contact may be included in this lamp circuit since the relay is certain to release following establishment of traffic in the stretch with the result that this lamp is certain to be lighted during occupancy of the stretch.

In the drawings,

Figs. 1A and 1B when placed together with Fig. 1A at the left form a diagram of a stretch of single track railroad equipped with wayside apparatus embodying our invention, and

Fig. 2 is a diagram showing C. T. C. machine circuits for use in connection with the apparatus shown in Figs. 1A and 1B.

Referring to Figs. 1A and 1B of the drawings there is shown therein a stretch of single track railway extending between two passing sidings and provided with wayside signal apparatus for authorizing traffic to move in one direction through the stretch at times and to move in the other direction at other times. In this application only the portions of the wayside apparatus essential to the understanding of this invention have been shown and the remainder of the apparatus may be arranged as shown in application for Letters Patent of the United States, Serial No. 501,204 of H. S. Young, filed September 4, 1943.

The equipment at the left-hand or west end of the stretch includes a C. T. C. system field station unit designated station 1-2, and the equipment at the right-hand or east end of the stretch includes a C. T. C. system field station unit designated station 3-4.

The field stations are connected with the office over a pair of line wires, not shown, by a code communication system which may be of the type shown in Letters Patent of the United States No. 2,229,249, issued January 21, 1941 to L. V. Lewis, or in application for Letters Patent of the United States, Serial No. 496,907, filed July 31, 1943, by A. P. Jackel, and described in Manual 506A of The Union Switch and Signal Company, Swissvale, Pa.

Consideration of the detailed mode of operation of the code communication system is not needed for an understanding of our invention and it is deemed sufficient to point out that a field station is provided at each end of each track stretch to be controlled and that coding units are provided at the office and at each field station and are connected by a pair of line wires, not shown, over which control codes are transmit-

ted at times from the office to the field stations, and at other times indication codes are transmitted over the same line wires from the different field stations to the office without interference.

5 Transmission of each code includes the temporary establishment of a plurality of communication channels, such, for example, as seven, between the office and a station to position a group of relays.

10 Each code includes a distinctive code call by means of which a selector relay 1-2S or 3-4S at the office and a similar relay, not shown, at one station only is energized to effect temporary establishment of seven control channels between 15 the office and the station. The different stations have different code calls, consequently the selector relays for different stations or panels are not energized at the same time, and the same channels provide communication at different times 20 with all of the stations.

The explanation of this invention requires only three channels employed in the transmission of control codes and five channels employed in the transmission of indication codes, and in order to 25 simplify the disclosure the other channels and related apparatus have not been shown.

The channels employed in the transmission of control codes are designated 2, 5 and 7, and the channels employed in the transmission of indication 30 codes are designated 10, 12, 13, 14 and 15, the numbers employed to designate these channels being the same as are employed to designate the corresponding channels in the above-identified application of H. S. Young.

35 It is to be understood that the system of our invention is made up of a number of unit portions generally similar to the one shown in the drawings, but as the invention may be fully understood from one such portion, only one has been 40 illustrated in the drawings.

The office and field stations and wayside signal 45 locations are each provided with a suitable source of direct current, such as a storage battery, not shown, the terminals of which are designated B and C in the drawings.

In most instances in the drawings the relay contacts are located directly under the winding of the associated relay, but in some cases in order to simplify the drawings, relay contacts are 50 separated from the relay winding, and in these instances the relay with which the contacts are associated is designated by appropriate reference characters placed above the contacts.

The equipment at each field station includes a 55 starting relay FST which responds to a change in the position of any of the associated indicating relays to provide connection from terminal B of a source of current to the indication channels to effect delivery of indication codes over the line wires during the time that a delivery relay D at the office is energized to thereby position a group of indication relays in accordance with the condition of energization of indication channels.

60 The means for controlling the field station starting relays FST is shown diagrammatically and these relays are controlled as explained in detail in the above-identified application of A. P. Jackel. The field station starting relays FST are 65 of the polarized type and each has contacts which normally occupy their left-hand or normal position from which they are moved to their right-hand or reverse position to initiate transmission of an indication code, while the relay contacts

70 normally occupy their left-hand or normal position from which they are moved to their right-hand or reverse position to initiate transmission of an indication code, while the relay contacts 75 are restored to their left-hand or normal posi-

tion in consequence of the transmission of an indication code by the associated field station.

The indication relays at the office governed from the field station 1-2 at the left-hand or west end of the single track stretch include a relay 1TK which is controlled by the track relay 1TR for section 1T; a signal indication relay 2RHK governed by relay 2RRGP which repeats the stop indications of the signals 2RA and 2RB; and a block indication relay 2RBK controlled by the relay 2RBP which in turn is governed by traffic conditions in the stretch as explained below.

The relays at the field station 3-4 at the right-hand end of the single track stretch function in a similar manner to control the relays 3TK, 4LHK and 4LBK at the office.

The block indication lamp BKE in the track diagram of the control machine is governed by the relays 2RBK and 4LBK, one of which indicates the condition of occupancy of a portion of the single track stretch and the other of which indicates the condition of occupancy of the remainder of the single track stretch. The lamp BKE is also controlled by the indication relays 1TK and 3TK for the detector sections at the ends of the stretch, and by the block indication repeater or auxiliary relay 2-4BKSR as herein-after explained.

The signal levers 2SIG and 4SIG on the panel of the control machine are the usual three-position levers for the code control of the signal control relays at the field stations at the opposite ends of the stretch. The levers 2SIG and 4SIG are electrically interlocked with respect to the control of train movements into the intervening single track stretch by the master directional polarized relay 2-4LP, as in the above-identified application of H. S. Young, and also in his Letters Patent of the United States No. 2,326,991. The relay 2-4LP has associated therewith relays 2-4LPS and 2-4BKSR which are governed substantially in the manner explained in detail in application for Letters Patent of the United States, Serial No. 567,188, filed by us on December 8, 1944.

The equipment is arranged so that, when energy is applied to channel 2 and a control code is transmitted to a field station, the traffic direction relay FS at that station is operated to condition the wayside apparatus to make that end of the stretch an exit or leaving end. Similarly, the equipment is arranged so that, when energy is not applied to channel 2 and a control code is transmitted to a field station, the traffic direction control relay FS is operated to condition the wayside apparatus to make that end of the stretch an entrance end so that the signal at that point may be controlled by the wayside circuits on operation of the associated signal relay.

The equipment is also arranged so that, when energy is supplied to the code channel governing a signal control relay such as, for example, channel 5 or 7, and a control code is transmitted to a field station, the signal control relay at that station is operated to render the signal subject to the control of the wayside circuits.

The signal levers 2SIG and 4SIG are of the three-position type and each has a center position N, a left-hand position L, and a right-hand position R. The levers control contacts which are shown diagrammatically in the drawings; the contacts which are closed in the left-hand position of the lever being designated L; those which are closed in the right-hand position of the lever being designated R; those which are closed in

either the normal or the left-hand position of the lever being designated NL; and those which are closed in either the normal or the right-hand position of the lever being designated NR.

5 The equipment at each field station includes a relay MSP, not shown, the contacts of which are picked up when the contacts of the associated starting relay FST are reversed to initiate transmission of an indication code and when picked up 10 remain picked up until transmission of the indication code is complete.

The equipment is shown in the condition which it assumes when the track stretch is vacant, the signals 2R and 4L are at stop, and the wayside signaling apparatus prepares the stretch for west-bound traffic, that is, governs the westbound intermediate signals 5L and 6L in accordance with traffic conditions in advance, and also controls relay 4LHD in accordance with traffic conditions 15 in advance so that signal 4LA or 4LB may be cleared on reversal of the signal control relay 4LHS. In addition, it is assumed that signal 2L is at stop so the relay 2LPC is released as this relay is governed by signal 2L and is released 20 when signal 2L is at stop and is picked up when this signal is at caution or clear. At this time the contacts 20 and 21 of the traffic directional relay 2WFSR at the left-hand or west end of the stretch are in their left-hand or normal positions and connect the line wires 23 and 24 over contacts 25 and 26 of relay 2LPC to a source of energy in series with an approach relay 2RAR. The energy supplied to the line wires 23 and 24 feeds over front contacts of track relays 1TR, 25 2TR and 4TR, over back contacts 27 and 28 of relay 5RPC, and back contacts 30 and 31 of relay 5RSR to the winding of signal 5L and causes this signal, when lighted, to display its yellow or caution indication. The energy supplied to 30 line wires 23 and 24 through the winding of relay 2RAR keeps contact 33 of the relay picked up so that it establishes the circuit including normal polar contact 32 of relay 2WFSR for energizing relay 2RBP and its contact 34 is picked up 35 to interrupt the circuit leading to terminal 14 of the C. T. C. field station unit so that indication codes sent to the office cause the contacts of relay 2RBK to occupy their normal or released position.

50 At this time signals 2RA and 2RB are at stop so the circuit of relay 2RRGP is complete and its contact 35 interrupts the supply of energy to terminal 15 of the C. T. C. system field station unit, and, as section 1T is vacant, contact 36 of 55 track relay 1TR is picked up and establishes the circuit of relay 1TKS so that it is held in its energized or normal position by energy supplied over its front contact 37 and contact 38 of relay 1TKS interrupts the circuit leading to terminal 10 of the field station unit. Accordingly, indication codes sent to the office from this station release the relays 2RHK and 1TK.

As signal 5L is conditioned to display its yellow indication, energy is supplied over back contact 65 G and front contact Y of the signal to relay 5LPC and its contacts are picked up to cause energy of normal polarity to be supplied to line wires 49 and 41 leading to the signal 6L. At this time wire 41 is connected to terminal C of a source over front contact 42 of relay 5LPC and wire 40 is connected over front contact 43 of relay 5LPC, front contact 45 of relay 4TR, winding of relay 5LAR and back contacts Y and G of signal 5R to terminal B of the source. The energy supplied to signal 6L causes it, when lighted, to

display its green or clear indication, while energy is supplied over back contact Y and front contact G of the signal 6L to relay 6LPC with the result that its contacts are picked up and cause energy of normal polarity to be supplied to line wires 48 and 49 over a circuit similar to that described above for line wires 40 and 41. This circuit includes in series therewith the approach relay 6LAR.

The energy supplied to line wires 48 and 49 is supplied over contacts 50 and 51 of relay 4EFSR in their right-hand or reverse position to a polar relay 4LHD to pick up its neutral contacts and to cause its polar contacts to occupy their left-hand or normal positions so that polar contact 53 and neutral contact 54 provide a circuit for relay 4LBP and its contact 56 is picked up to interrupt the supply of energy to terminal 12 of the field station unit so that indication codes sent to the office cause the contacts of relay 4LBK to occupy their normal or released position.

As shown, contacts 58 and 59 of relay 4LHSR are in their left-hand or normal positions and interrupt the circuits for supplying energy to the windings of signals 4LA and 4LB and these signals are both at stop and establish the circuit of relay 4LRGP so that its contact 60 interrupts the supply of energy to terminal 13 of the field station unit. As section 3T is vacant, relay 3TR is picked up and its contact 61 establishes connection from terminal C of the source to one terminal of the winding of relay 3TKS, while connection is established from the other terminal of the relay winding to terminal B of the source over front contact 62 of the relay, and also over normal polar contact 63 of starting relay 3-4FST and back contact 64 of the relay MSP of the C. T. C. field station unit. Accordingly, the contacts of relay 3TKS occupy their normal or picked-up position and its contact 65 interrupts the circuit leading to terminal 10 of the field station unit, and the indication codes sent to the office release relays 4LHK and 3TK.

Referring to Fig. 2, which shows the equipment at the office, the contacts of relay 2-4LP are in their left-hand or normal position in which they designate westbound traffic in the stretch shown in Figs. 1A and 1B. In addition, at this time, relay 2-4LPS is energized by current supplied over its stick circuit and the auxiliary or block indication repeater relay 2-4BKSR is released. As relays 1TK, 3TK, 2RBK, 4LBK, 2RHK and 4LHK are all released, energy may be supplied to one or the other of the windings of relay 2-4LP on movement of the signal lever 2SIG or 4SIG to thereby move the contacts of relay 2-4LP if the operator wishes to change the designated traffic direction.

For purposes of illustration it will be assumed that the operator wishes to clear the signal 4LA to authorize a westbound train to enter the stretch. In order to clear this signal he moves lever 4SIG to its left-hand position L and presses the starting button 3-4STB to pick up the starting relay 3-4ST and cause a control code to be sent to field station 3-4. On this movement of lever 4SIG the circuit is established to supply energy to the lower winding of relay 2-4LP but as its contacts are already in their left-hand position the supply of energy to this winding is without effect.

During transmission of this control code, relay 3-4S picks up so that the code sent to station 3-4 is determined by the condition of control circuits individual to this station. This is the case since

energization of the input terminals of the office coding unit is governed by circuits including front contacts of the relay 3-4S. When relay 3-4S picks up energy is supplied over normal polar contact 70 of relay 2-4LP, front contact 71 of relay 3-4S, and contact L of lever 4SIG to terminal 5 of the office coding unit and the control code sent to station 3-4 causes energy to be supplied to relay 4LHSR to move its contacts 58 and 59 to their right-hand position to establish the circuit controlled by contacts of relay 4LHD and by switch controlled contacts 90 and 91 for supplying energy to signal 4LA and this signal is caused to display its green or clear indication. When the signal 4LA clears, the circuit of relay 4LRGP is interrupted and it releases so that its contact 69 establishes the circuit to supply energy to terminal 13 of the field station unit. In addition, on release of relay 4LRGP, a contact of the relay momentarily interrupts the circuit of the starting relay 3-4FST and reverses its contacts to cause an indication code to be sent to the office to pick up relay 4LHK.

At this time contact 63 of relay 3-4FST interrupts the pick-up circuit for relay 3TKS but this relay is energized by current supplied over its stick circuit established by its contact 62 and the relay remains picked up so that its contact 65 interrupts the supply of energy to terminal 10 of the field station.

If a westbound train now enters the stretch, the track relay 3TR will release when the train enters section 3T. On release of relay 3TR its contact 72 establishes for relay 4LBP a stick circuit including reverse polar contact 13 of relay 4EFSR so that the contacts of relay 4LBP remain in their normal or picked-up position after release of neutral contact 54 of relay 4LHD as a result of interruption of the circuit of relay 4LHD by contacts 96 and 97 of relay 3TR.

On release of relay 3TR its contact 61 interrupts the circuit of relay 3TKS and it releases or is operated to interrupt its own stick circuit while its contact 71 establishes for relay 4LBP a stick circuit including reverse polar contact 73 of relay 4EFSR so that the contacts of relay 4LBP remain in their picked up or normal position as long as relay 3TKS is released.

On release of relay 4LHD the signal 4LA is put to stop and the circuit of relay 4LRGP is established so that its contact 69 interrupts the supply of energy to terminal 13 of the field station.

After release of relays 3TR and 3TKS energy is supplied over back contact 61 of relay 3TR and back contact 78 of relay 3TKS to the lower winding of relay 4LHSR to move the relay contacts to their normal positions and prevent clearing of signal 4LA unless another control code is sent to this station.

As a result of the changes at this station the starting relay 3-4FST is reversed and an indication code is sent to the office to pick up relay 3TK, release relay 4LHK, and to keep relay 4LBK in its normal or released position since relay 4LBP is energized by current supplied over its stick circuit. When relay 3TK picks up, its contact 98 interrupts the circuits of relay 2-4LP to prevent movement of its contacts and thus insure that westbound traffic is maintained in the stretch.

In addition, when relay 3TK picks up, its contact 80 establishes a circuit for the block lamp 2-4BKE so that this lamp is lighted to indicate that the block is occupied, while another contact 75 of relay 3TK establishes a circuit for lamp 3TKE

and it is lighted to show that section 3T is occupied.

At the end of the indication code sent from field station 3-4 the relay MSP is released and the contact 63 of relay 3-4FST is restored to its normal position.

When the train advances into section 8T, the track relay 8TR releases and interrupts the line wires 48 and 49 so relay 4LHD remains released, while these wires are also interrupted when the train enters section 1T and relay 1TR releases.

When the train vacates section 3T, the relay 3TR picks up and energy is supplied to relay 3TKS over its pick-up circuit which includes front contact 61 of relay 3TR, normal polar contact 63 of relay 3-4FST, and back contact 64 of relay MSP, assuming that the indication code is sent to the office before section 3T is vacated. Accordingly, relay 3TKS picks up or is restored from its released or operated position to its normal position and its contact 62 establishes the relay stick circuit to keep the relay contacts picked up during subsequent reversal of the contacts of relay 3-4FST.

When relays 3TR and 3TKS pick up, their contacts 72 and 77 interrupt the stick circuit for relay 4LBP and its contacts release or move to their operated position as the relay pick-up circuit is opened by neutral contact 54 of relay 4LHD.

When relay 3TKS picks up, the contact of this relay in the circuit of relay 3-4FST momentarily interrupts the circuit of this relay and its contacts reverse to cause an indication code to be sent to the office. As the contacts of relay 3TKS are in their picked up or normal position, contact 65 interrupts the supply of energy to terminal 10 of the field station unit, and, as relay 4LBP is released, its contact 55 establishes the circuit to terminal 12 of the field station unit, and the indication code sent to the office releases the relay 3TK and picks up or operates relay 4LBK. On release of relay 3TK its contact 89 interrupts one circuit for lighting lamp 2-4BKE, but at this time energy is supplied to this lamp over front contact 81 of relay 4LBK and back contact 82 of relay 2-4BKS and this lamp remains lighted to indicate that the stretch is occupied. In addition, as relay 3TK is released the lamp 3TKE is extinguished and contact 98 in the circuits of relay 2-4LP is closed, but at this time contact 99 of relay 4LBK interrupts the circuits of relay 2-4LP and therefore insures that the contacts of relay 2-4LP will remain in their left-hand position and maintain westbound traffic in the stretch.

When the train advances into section 6T, the track relay 6TR releases and interrupts the circuit of signal 6L and this signal displays its red or stop indication while the circuit of relay 6LPC is interrupted and it releases. In addition, on release of relay 6TR energy is supplied to relay 6LSR over its pick-up circuit prior to release of relay 6LPC and relay 6LSR picks up to establish a stick circuit to maintain it energized as long as relay 6LPC is released, while relay 6LSR establishes a circuit to supply energy of reverse polarity to line wires 48 and 49. When the train vacates sections 8T and 1T, the energy supplied to line wires 48 and 49 feeds to relay 4LHD and picks up its neutral contacts and operates the relay polar contacts to their right-hand positions. Accordingly, contact 53 of relay 4LHD interrupts the circuit of relay 4LBP and it remains released or operated and maintains the supply of energy

to terminal 12 of the field station unit so that indication codes sent to the office show that the block is occupied.

When the train advances into section 4T, the signal 5L is put to stop and relay 5LSR is picked up while relay 5LPC is released. Accordingly, energy of reverse polarity is supplied to line wires 40 and 41, but the circuit of these wires is interrupted as long as section 5T is occupied and relay 5TR is released. In addition, when relay 4TR releases and interrupts the circuit of line wires 23 and 24, the relay 2RAR releases and its contact 33 interrupts the circuit of relay 2RBP so that its contacts move to their released or operated position in which contact 34 establishes the circuit to supply energy to terminal 14 of the field station unit. Also, on release of relay 2RBP, a contact of the relay momentarily interrupts the circuit of relay 1-2FST and its contacts reverse to cause an indication code to be sent to the office to pick up or operate relay 2RBK so that its contact 84 establishes a circuit to maintain lamp 2-4BKE lighted after release of contact 81 of relay 4LBK. When relay 2RBK picks up or is operated, its contact 85 interrupts the circuits of relay 2-4LP to prevent energization of this relay after release of contact 99 of relay 4LBK.

When the train vacates section 5T and relay 5TR picks up, the energy of reverse polarity supplied to line wires 40 and 41 feeds to the winding of signal 6L to cause it to display its yellow or caution indication when lighted, while the contacts controlled by the signal mechanism establish the circuit of relay 6LPC and it picks up to release relay 6LSR and to supply energy of normal polarity to line wires 48 and 49. This energy keeps the neutral contacts of relay 4LHD picked up and moves the relay polar contacts to their left-hand or normal position in which contact 53 establishes the circuit of relay 4LBP and its contacts move to their picked-up or normal position in which contact 56 interrupts the supply of energy to terminal 12 of the field station unit. In addition, a contact of relay 4LBP momentarily interrupts the circuit of relay 3-4FST and its contacts reverse to cause an indication code to be sent to the office to release or restore to normal the contacts of relay 4LBK, but the lamp 2-4BKE continues to be lighted by energy supplied over contact 84 of relay 2RBK while the circuits of relay 2-4LP are interrupted by contact 85 of relay 2RBK.

Movement of the westbound train out of the stretch is governed by signal 2L which may be controlled from the office by the operator in any suitable manner. The details of the control of this signal are not essential to an understanding of this invention and are being omitted to simplify this disclosure.

If signal 2L is cleared, the train may advance into section 1T thereby releasing the track relay 1TR so that its contact 36 interrupts the circuit of relay 1TKS and its contacts move to their released or operated position in which contact 38 establishes the circuit for supplying energy to terminal 10 of the field station unit while the contacts of relay 1-2FST are reversed to cause an indication code to be sent to the office to pick up relay 1TK and to keep relay 2RBK picked up or operated.

When the train vacates the stretch, the relay 1TR picks up and completes the circuit of the line wires so that relay 2RAR picks up, while the mechanism of signal 5L establishes the circuit of relay 5LPC and it picks up to release relay 5LSR

11

and to cause energy of normal polarity to be supplied to line wires 40 and 41. In addition, when relay 1TR picks up, its contact 36 establishes the circuit of relay 1TKS and its contacts move to their normal or picked-up position to establish the relay stick circuit, while its contact 38 interrupts the supply of energy to terminal 10 of the field station unit.

When relay 2RAR picks up, its contact 33 establishes the circuit of relay 2RBP and its contacts move to their normal or picked-up position to interrupt the supply of energy to terminal 14 of the field station unit, while at this time the circuit of relay 1-2FST is momentarily interrupted and its contacts are reversed to cause an indication code to be sent to the office to release relays 2RBK and 1TK, thereby extinguishing the lamps 1TKE and 2-4BKE and establishing the circuits of relays 2-4LP.

If the operator wishes to prepare the track stretch for eastbound traffic, he may do so by moving lever 4SIG to its center or its right-hand position and moving lever 2SIG to its right-hand position, thereby establishing the circuit of the upper winding of relay 2-4LP and moving its contacts to their right-hand or reverse positions. On this movement of the contacts of relay 2-4LP, the polarity of the energy supplied to relay 2-4LPS is changed and it releases to interrupt its own stick circuit and to establish circuits for relays 2RBK, 4LBK and 2-4BKSR which pick up or are operated and establish stick circuits for themselves. At this time contact 88 of the auxiliary or block indication repeater relay 2-4BKSR shunts the contacts 85 and 99 of relays 2RBK and 4LBK in the circuits of relay 2-4LP and permits operation of relay 2-4LP to change the designated traffic direction even though relays 2RBK and 4LBK are operated or picked up.

If either starting button 1-2STB or 3-4STB is now pressed, the starting relays 1-2ST and 3-4ST are both picked up to initiate transmission of control codes to the field stations at both ends of the stretch, while at this time energy is supplied to relay 2-4LPS over its pick-up circuit and its contacts pick up to establish the relay stick circuit. The energy which is supplied to the pick-up circuit for relay 2-4LPS is supplied from terminal 51 of the office coding unit. As explained in application Serial No. 496,907 of A. P. Jackel, energy is supplied to this terminal when and only when the office coding unit is conditioned to transmit a code. As long as relay 2-4LPS is released it establishes circuits for relays 2RBK and 4LBK, and this arrangement for delaying energization of relay 2-4LPS until the office coding unit is in condition to transmit prevents premature release of relay 2RBK or 4LBK by an indication code received after reversal of relay 2-4LP to change the designated traffic direction, but prior to transmission of control codes to cause the wayside equipment to prepare the stretch for traffic in the new direction. When relay 2-4LPS picks up, it interrupts the pick-up circuit for the auxiliary or block indication repeater relay 2-4BKSR, but it remains picked up until relays 2RBK and 4LBK are both released or restored to normal, while after picking up of relay 2-4LPS the relays 2RBK and 4LBK remain operated or picked up until suitable indication codes are received from the field stations.

The control code sent to field station 1-2 at this time reverses the contacts of relay 2WFSR, and the control code sent to field station 3-4 moves the contacts of relay 4EFSR to their nor-

12

mal position. In addition, during transmission of the control code to station 1-2 the starting relay 1-2ST at the office is released, while the starting relay 3-4ST is released during transmission of the control code to station 3-4.

When relay 2WFSR reverses, its contacts 20 and 21 interrupt the supply of energy to line wires 23 and 24 and connect these wires to relay 2RHD. At this time relay 2RAR releases and its contact 33 interrupts the circuit of relay 2RBP and its contacts move to their released or operated position to cause an indication code to be sent to the office which maintains relay 2RBK operated or picked up. When the supply of energy to wires 23 and 24 is cut off the winding of signal 5L is deenergized and the contacts operated by the signal interrupt the circuit of relay 5LPC and it releases to interrupt the supply of energy to line wires 40 and 41 so that signal 6L is deenergized and interrupts the circuit of relay 6LPC. Accordingly, relay 6LPC releases and interrupts the supply of energy to wires 48 and 49 and connects these wires to the winding of signal 6R.

When the contacts of relay 4EFSR are moved to their normal position, the relay 4LHD is deenergized and its neutral contact 54 interrupts the circuit of relay 4LBP. After reversal of the contacts of relay 4EFSR, energy is supplied to line wires 48 and 49 through the winding of relay 4LAR and relay 4LAR picks up and its contact 89 establishes a circuit for relay 4LBP and it picks up so that indication codes sent from field station 3-4 to the office release or restore to normal the contacts of relay 4LBK, but at this time relay 2-4BKSR is maintained energized by current supplied over the stick circuit established by contact 95 of relay 2RBK.

The current supplied through the winding of relay 4LAR to line wires 48 and 49 is of one polarity or the other depending on the position of pole changing contacts which may be governed in any suitable manner. The energy supplied to line wires 48 and 49 energizes the winding of signal 6R so the contacts of the signal establish the circuit of relay 6RPC and it picks up to cause energy of normal polarity to be supplied to line wires 40 and 41. The current supplied to these wires energizes signal 5R so it establishes the circuit of relay 5RPC and it picks up to cause current of normal polarity to be supplied to wires 23 and 24. This energy picks up the neutral contacts of relay 2RHD and moves the relay contacts to their normal position. If the control code sent to station 1-2 reversed the contacts of relay 2RHSR, one or the other of the signals 2RA or 2RB will be cleared to authorize an eastbound train to enter the stretch.

When energy of normal polarity is supplied to relay 2RHD, its polar contact 90 and its neutral contact 91 establish the circuit of relay 2RBP and its contacts move to their normal or picked-up position to interrupt the circuit leading to terminal 14 of the field station unit so that indication codes sent to the office release or restore to normal the contacts of relay 2RBK, thereby interrupting the stick circuit for the auxiliary or block indication repeater relay 2-4BKSR to cause it to release and interrupt the circuit shunting contacts 85 and 99 of relays 2RBK and 4LBK in the circuits of relay 2-4LP so that relay 2-4LP is now controlled by relays 2RBK and 4LBK, and is subject to traffic conditions in the stretch, while contact 82 of relay 2-4BKSR establishes the circuit of the lamp 2-4BKE.

If one of the signals 2RA or 2RB had cleared

before the indication code was sent to the office, the relay 2RRGP at the field station would have been released and the indication sent to the office will pick up relay 2RHK so that its contact 3 interrupts the circuits of relay 2-4LP.

Because of use of the C. T. C. line wires for transmission of control codes, or for the transmission of indication codes from other field stations, the field station 1-2 may not be able to transmit an indication code to the office for a 10 substantial time interval subsequent to establishment of eastbound traffic in the stretch and resultant picking up of relay 2RBP, and also of clearing of one of the signals 2RA or 2RB. A train may enter the stretch immediately after 15 clearing of one of the signals 2RA or 2RB and when the train advances into section 1T, it releases track relay 1TR so that its contacts interrupt the line wires 23 and 24 to deenergize the relay 2RHD, while contact 36 of relay 1TR interrupts the circuit of relay 1TKS and it releases or is operated with the result that energy is supplied to the lower winding of relay 2RHSR over back contact 94 of relay 1TKS and back contact 36 of relay 1TR. The energy supplied to relay 25 2RHSR over this circuit restores the relay contacts to their normal position so the signals 2RA or 2RB are held at stop.

If, on release of the relay 2RHD and consequent interruption by its neutral contact 91 of the circuit of the relay 2RBP, the contacts of relay 2RBP should move to their operated or released position, its contact 34 would establish the circuit for supplying energy to terminal 14 of the field station unit so that indication codes thereafter sent to the office would keep the relay 2RBK operated or picked up, and its contact 95 would maintain the stick circuit of relay 2-4BKSR. Under these conditions, therefore, relay 2-4BKSR would remain energized and its contact 88 would maintain the circuit shunting contacts 85 and 99 of relays 2RKB and 4LBK in the circuits of relay 2-4LP, and the operator would be free to energize the relay 2-4LP to move its contacts and change the designated traffic direction even though the stretch is occupied. If the contacts of relay 2-4LP should be moved and a control code should be sent to station 3-4, relay 4LFSR would be reversed and the supply of energy to line wires 48 and 49 would be cut off with resultant deenergization of the other line circuits and display of stop indications by signals 6R and 5R. The presence of the train in the stretch would prevent clearing of the signals governing movement of westbound traffic in the stretch but 55 the interference with the signals governing eastbound traffic is objectionable and would delay traffic, and this system is arranged to eliminate the possibility of the difficulty just described.

Referring to Fig. 1A, it will be seen that on 60 release of relay 1TR its contact 100 establishes for relay 2RBP the stick circuit including its own front contact 101 and reverse polar contact 32 of relay 2WFSR, while on movement of the contacts of relay 1TKS to their released or operated position contact 102 establishes another stick circuit for relay 2RBP. Accordingly, on entrance of a train into the stretch, the contacts of relay 2RBP remain in their normal or picked-up position after release of relay 2RHD so contact 34 of 70 relay 2RBP continues to interrupt the circuit leading to terminal 14 of the field station unit.

The pick-up circuit for relay 1TKS is controlled by contacts of relays 1-2FST and MSP so that the contacts of relay 1TKS are certain 75

to remain in their released or operated position until an indication code is sent to the office, and as relay 1TKS when released establishes a stick circuit for relay 2RBP, the contacts of relay 2RBP are certain to remain in their picked up or normal position until an indication code is sent to the office.

When an indication code is sent to the office with relay 1TKS operated or released and the contacts of relay 2RBP in their normal or picked up position, the relay 1TK is picked up and the relay 2RBK is released so that its contact 95 interrupts the stick circuit for relay 2-4BKSR and it releases with the result that its contact 88 interrupts the circuit shunting contacts 85 and 99 of relays 2RKB and 4LBK in the circuits of relay 2-4LP. At this time contacts 85 and 99 are released, but the circuits of relay 2-4LP are interrupted by contact 87 of relay 1TK so the contacts of relay 2-4LP cannot be moved.

In addition, on release of relay 2-4BKSR, its contact 82 establishes the circuits governed by relays 2RKB and 4LBK for lighting lamp 2-4BKE but at this time this lamp is lighted by current supplied over front contact 86 of relay 1TK.

When the train vacates section 1T, the relay 1TR picks up and its contact 36 establishes the pick-up circuit for relay 1TKS, assuming that an indication code has been sent to the office so that this circuit is established by relays 1-2FST and MSP. When relays 1TK and 1TKS are both picked up, the stick circuits for relay 2RBP are interrupted and its contacts move to their normal or released position to establish the circuit for supplying energy to terminal 14 of the field station unit. The indication code now sent to the office releases relay 1TK and picks up or operates relay 2RBK so that lamp 2-4BKE is lighted by energy supplied over back contact 82 of relay 2-4BKSR and front contact 84 of relay 2RBK. In addition, on picking up of relay 2RBK, its contact 85 interrupts the circuits of relay 2-4LP to prevent movement of the contacts of this relay after closing of contact 87 of relay 1TK. The contact 85 of relay 2RBK is certain to be effective to prevent energization of relay 2-4LP at this time, since, as explained above, the relay 2-4BKSR is certain to be released so that its contact 88 interrupts the circuit shunting contact 85 of relay 2RBK.

The C. T. C. field station units are arranged so that, after a station has transmitted an indication code, it cannot thereafter transmit another indication code if another station has an indication stored for transmission. Accordingly, if, at the time a train enters the stretch and station 1-2 sends an indication code to the office which releases relay 2RBK, an indication code has not been sent from station 3-4 to release relay 4LBK, the indication code sent from station 1-2 to pick up relay 2RBK will not be transmitted until after the indication code has been sent from station 3-4 to release relay 4LBK. As a result, relays 2RBK and 4LBK are certain to both be released for at least a short time interval, so the stick circuit for relay 2-4BKSR is interrupted to insure release of relay 2-4BKSR.

It will be seen, therefore, that during occupancy of the stretch the circuits of relay 2-4LP are interrupted by contact 87 of relay 1TK or by contact 85 of relay 2RBK so there is no possibility that the contacts of relay 2-4LP can be moved during occupancy of the stretch. Ac-

cordingly, the established traffic direction will be maintained during occupancy of the stretch.

As the relay 2-4BKSR is certain to be released following a change in the direction of traffic in a stretch, back contact 82 of relay 2-4BKSR may be included in the circuits governed by relays 2RBK and 4LBK for lighting lamp 2-4BKE, and thereby prevent lighting of this lamp when relay 2RBK or 4LBK is operated or picked up incident to a change in the direction of traffic in a stretch, but at the same time insuring that this lamp will be lighted when one of these relays is operated or picked up because of occupancy of the stretch. This elimination of undesired lighting of lamp 2-4BKE when relay 2RBK or 4LBK is picked up because of a change in the direction of traffic in a stretch makes this lamp more effective to show occupancy of the stretch and simplifies the work of the C. T. C. machine operator.

On continued movement of the eastbound train through the stretch the equipment operates in the usual manner, and a detailed explanation of the operation of the equipment at such times is unnecessary, except to point out that, when the eastbound train advances beyond signal 6R, the circuit of line wires 48 and 49 is interrupted and relay 4LAR releases so that its contact 89 interrupts the circuit of relay 4LBP and it is operated or released to cause a block occupied indication code to be sent to the office. When the eastbound train enters section 3T, the relays 3TR and 3TKS release but the stick circuit for relay 4LBP is not established as this circuit is interrupted by a contact of relay 4LBP, and also by contact 73 of relay 4EFSR which occupies its normal position at this time.

Although the invention has been illustrated and described in connection with a stretch of track equipped with wayside apparatus which is arranged so that traffic conditions in a portion of the stretch are indicated from one end of the stretch and traffic conditions in the remainder of the stretch are indicated from the other end of the stretch, it should be understood that the invention is not limited to this arrangement but is applicable also to stretches in which traffic conditions throughout a stretch are indicated from one end or the other of the stretch.

Similarly, although the invention has been illustrated and described in connection with a stretch of track equipped with wayside signaling apparatus governed over line wires, the invention is also applicable to stretches equipped with other forms of wayside signaling apparatus, such, for example, as coded track circuit signaling equipment.

Although we have illustrated and described one form of railway signaling apparatus embodying our invention, it should be understood that various changes and modifications may be made therein within the scope of the appended claims without departing from the spirit and scope of our invention.

Having thus described our invention, what we claim is:

1. In a system of centralized traffic control for a stretch of single track railroad between the ends of adjacent passing sidings and equipped with a code type communication system connecting the ends of said stretch with a control office, said code communication system including at each end of the stretch a starting relay having contacts which are moved from a normal to an operated position in response to a change in apparatus

paratus conditions at that location and are restored to their normal position in response to transmission of an indication code from that location to the office, in combination, a block relay at each end of the stretch controlling transmission of indication codes to the office to show traffic conditions in the stretch, a system of reversible circuits extending the length of said track stretch and governed by traffic conditions in the stretch, said system of circuits being manually controlled from said office through said code communication system so as to at times prepare the stretch for traffic in one direction and to at other times prepare the stretch for traffic in the other direction, said system of circuits being operative when conditioned to prepare the stretch for traffic in either direction to control the signal and a block indication control circuit at the corresponding entrance end of the stretch in accordance with traffic conditions in at least a portion of said stretch, a detector track section at each end of the stretch including the track switch for connecting the track stretch with the adjacent passing siding, each detector track section being provided with a track circuit including a track relay, each detector section track relay having associated therewith a detector section repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts of the associated starting relay are in their normal position, means for each of said block relays for moving its contacts from an operated to a normal position when the associated block indication control circuit shows that the track stretch over which it is controlled is unoccupied, means effective on movement of the contacts of a detector section repeater relay to their operated position when the contacts of the associated block relay are in their normal position to maintain the contacts of said block relay in their normal position as long as the detector section repeater relay contacts are in their operated position, each detector section repeater relay governing a detector section indication relay at the office through said code communication system and each block relay governing a block indication relay at the office through said code communication system, and means at said office governed by the detector section and block indication relays associated with said track stretch for governing transmission of control codes by said code communication system to cause said system of reversible circuits to maintain the established direction of traffic during occupancy of said stretch.

2. In a system of centralized traffic control for a stretch of single track railroad between the ends of adjacent passing sidings and equipped with a code type communication system connecting the ends of said stretch with a control office, said code communication system including at each end of the stretch a starting relay having contacts which are moved from a normal to an operated position in response to a change in apparatus conditions at that location and are restored to their normal position in response to transmission of an indication code from that location to the office, in combination, a block relay at each end of the stretch controlling transmission of indication codes to the office to show traffic conditions in the stretch,

a system of reversible circuits extending the length of said track stretch and governed by traffic conditions in the stretch, said system of circuits being manually controlled from said office through said code communication system so as to at times prepare the stretch for traffic in one direction and to at other times prepare the stretch for traffic in the other direction, said system of circuits being operative when conditioned to prepare the stretch for traffic in either direction to control the signal and a block indication control circuit at the corresponding entrance end of the stretch in accordance with traffic conditions in at least a portion of said stretch, a detector track section at each end of the stretch including the track switch for connecting the track stretch with the adjacent passing siding, each detector track section being provided with a track circuit including a track relay, each detector section track relay having associated therewith a detector section repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts of the associated starting relay are in their normal position, means for each of said block relays for moving its contacts from an operated to a normal position when the associated block indication control circuit shows that the track stretch over which it is controlled is unoccupied, means effective on movement of the contacts of a detector section repeater relay to their operated position when the contacts of the associated block relay are in their normal position to maintain the contacts of said block relay in their normal position as long as the detector section repeater relay contacts are in their operated position, each detector section repeater relay governing a detector section indication relay at the office through said code communication system and each block relay governing a block indication relay at the office through said code communication system, a block repeater relay at the office, means for moving the contacts of said block repeater relay from a normal to an operated position when the designated direction of traffic in said stretch is changed, means for moving the contacts of said block repeater relay to their normal position when said block indication relays are positioned by indication codes which show that the stretch is unoccupied, and means at said office governed by the detector section and block indication relays and by the block repeater relay associated with said track stretch for governing transmission of control codes by said code communication system to cause said system of reversible circuits to maintain the established direction of traffic during occupancy of said stretch.

3. In a system of centralized traffic control for a stretch of single track railroad between the ends of adjacent passing sidings and equipped with a code type communication system connecting the ends of said stretch with a control office, said code communication system including at each end of the stretch a starting relay having contacts which are moved from a normal to an operated position in response to a change in apparatus conditions at that location and are restored to their normal position in response to transmission of an indication code from that location to the office, in combination, a block relay at each end

of the stretch controlling transmission of indication codes to the office to show traffic conditions in the stretch, a system of reversible circuits extending the length of said track stretch and governed by traffic conditions in the stretch, said system of circuits being manually controlled from said office through said code communication system so as to at times prepare the stretch for traffic in one direction and to at other times prepare the stretch for traffic in the other direction, said system of circuits being operative when conditioned to prepare the stretch for traffic in either direction to control the signal and a block indication control circuit at the corresponding entrance end of the stretch in accordance with traffic conditions in at least a portion of said stretch, a detector track section at each end of the stretch including the track switch for connecting the track stretch with the adjacent passing siding, each detector track section being provided with a track circuit including a track relay, each detector section track relay having associated therewith a detector section repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts of the associated starting relay are in their normal position, means for each of said block relays for moving its contacts from an operated to a normal position when the associated block indication control circuit shows that the track stretch over which it is controlled is unoccupied, means effective on movement of the contacts of a detector section repeater relay to their operated position when the contacts of the associated block relay are in their normal position to maintain the contacts of said block relay in their normal position as long as the detector section repeater relay contacts are in their operated position, each detector section repeater relay and each block relay acting through said code communication system according as its contacts occupy their normal or their operated position to cause the contacts of a detector section or a block indication relay at the office to occupy their normal or their operated positions, a block repeater relay at the office, means for moving the contacts of said block repeater relay from their normal to their operated position when the designated direction of traffic in said stretch is changed, means for moving the contacts of said block repeater relay to their normal position when said block indication relays are positioned by indication codes which show that the stretch is unoccupied, and means at said office effective to maintain the established direction of traffic in said stretch when the contacts of the block indication relay controlled by the block relay at the designated entrance end of the stretch occupy their operated position provided the contacts of said block repeater relay occupy their normal position or when the contacts of the indication relay for the detector section at the entrance end of the stretch occupy their operated position.

4. In a system of centralized traffic control for a stretch of single track railroad connected at the ends by track switches with adjacent passing sidings and equipped with a code type communication system connecting the ends of said stretch with a control office, said code communication system including at each end of the stretch a

starting relay having contacts which are moved from a normal to an operated position in response to a change in apparatus conditions at that location and are restored to their normal position in response to transmission of an indication code from that location to the office, in combination, a detector track section at each end of the stretch including the associated track switch and provided with a track circuit including a track relay, a system of reversible circuits extending the length of said stretch and governed by traffic conditions in the stretch, said system of circuits being adapted to at times prepare the stretch for traffic in one direction and to at other times prepare the stretch for traffic in the other direction, said system of circuits being operative when conditioned to prepare the stretch for traffic in either direction to control the signal and a block indication control circuit at the corresponding entrance end of the stretch in accordance with traffic conditions in at least a portion of said stretch, manually controlled electroresponsive means at said office for designating the direction of traffic movements in said stretch and controlling the transmission of control codes by said code communication system by which said system of reversible circuits is conditioned to prepare the stretch for traffic in one direction or the other, each detector section track relay having associated therewith a detector section repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts of the associated starting relay are in their normal position, a block relay at each end of the stretch, means for each of said block relays for moving its contacts from an operated to a normal position when the associated block indication control circuit shows that the track stretch over which it is controlled is unoccupied, means effective when the contacts of a detector section repeater relay are moved to their operated position and the contacts of the associated block relay are in their normal position to maintain the contacts of said block relay in their normal position as long as the contacts of said detector section repeater relay remain in their operated position, said detector section repeater and block relays governing transmission of indication codes to the office by said code communication system, and means at said office controlled by the indication codes governed by the detector section repeater and block relays associated with said stretch and controlling the electro-responsive means for said stretch to maintain the established direction of traffic during occupancy of the stretch.

5. In a system of centralized traffic control for a stretch of single track railroad connected at the ends by track switches with adjacent passing sidings and equipped with a code type communication system connecting the ends of said stretch with a control office, said code communication system including at each end of the stretch a starting relay having contacts which are moved from a normal to an operated position in response to a change in apparatus conditions at that location and are restored to their normal position in response to transmission of an indication code from that location to the office, in combination, a detector track section at each end of the stretch

including the associated track switch and provided with a track circuit including a track relay, a system of reversible circuits extending the length of said stretch and governed by traffic conditions in the stretch, said system of circuits being adapted to at times prepare the stretch for traffic in one direction and to at other times prepare the stretch for traffic in the other direction, said system of circuits being operative when conditioned to prepare the stretch for traffic in either direction to control the signal and a block indication control circuit at the corresponding entrance end of the stretch in accordance with traffic conditions in at least a portion of said stretch, manually controlled electroresponsive means at said office for designating the direction of traffic movements in said stretch and controlling the transmission of control codes by said code communication system by which said system of reversible circuits is conditioned to prepare the stretch for traffic in one direction or the other, each detector section track relay having associated therewith a repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts of the associated starting relay are in their normal position, a block relay at each end of the stretch, means for each of said block relays for moving its contacts from an operated to a normal position when the associated block indication control circuit shows that the track stretch over which it is controlled is unoccupied, means effective when the contacts of a detector section repeater relay are moved to their operated position and the contacts of the associated block relay are in their normal position to maintain the contacts of said block relay in their normal position as long as the contacts of said detector section repeater relay remain in their operated position, detector section indication relays at the office governed through said code communication system in accordance with the position of the contacts of said detector section repeater relays, block indication relays at said office governed through said code communication system in accordance with the position of the contacts of said block relays, and means including said detector section and block indication relays for controlling said electroresponsive means to cause it to maintain the established direction of traffic in said stretch during occupancy thereof.

6. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from said office through said code

communication system to at times prepare said stretch for traffic in said given direction, a signal at the entrance end of said stretch governed by said system of circuits, a block relay at the entrance end of said stretch, means governed by said system of circuits for moving the block relay contacts from their operated to their normal position when said system of circuits prepares said stretch for traffic and for thereafter maintaining said relay contacts in their operated position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, means effective when the contacts of said detector section repeater relay are moved to their operated position and the contacts of said block relay occupy their normal position to maintain the contacts of said block relay in their normal position as long as the contacts of said detector section repeater relay occupy their operated position, a detector section indication relay at the office governed through said code communication system in accordance with the position of the contacts of said detector section repeater relay, a block indication relay at the office governed through said code communication system and having contacts which are moved to a normal or to an operated position in accordance with the position of the contacts of said block relay, a block repeater relay at the office having contacts which occupy an operated position when said stretch is not prepared for traffic, means for moving the contacts of said block repeater relay to a normal position when said block indication relay responds to an indication code transmitted from the entrance end of said stretch while the contacts of said block relay occupy their normal position, means effective provided the contacts of said block repeater relay are in their normal position for maintaining them in such position when the block indication relay responds to an indication code transmitted while the contacts of said block relay are in their operated position, and means governed by said detector section indication relay and by said block indication and block indication repeater relays and operating through said code communication system for causing said system of circuits to maintain traffic in said stretch.

7. In a system centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from

said office through said code communication system to at times prepare said stretch for traffic in said given direction, a signal at the entrance end of said stretch governed by said system of circuits, a block relay at the entrance end of said stretch, means governed by said system of circuits for moving the block relay contacts from their operated to a normal position when said system of circuits prepares said stretch for traffic and for thereafter maintaining said relay contacts in their normal position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, means effective when the contacts of said detector section repeater relay are moved to their operated position and the contacts of said block relay occupy their normal position to maintain the contacts of said block relay in their normal position as long as the contacts of said detector section repeater relay occupy their operated position, a block indication relay at the office governed through said code communication system and having contacts which are moved to a normal or to an operated position in accordance with the position of the contacts of said block relay, a block repeater relay at the office having contacts which occupy an operated position when said stretch is not prepared for traffic, means for moving the contacts of said block repeater relay to a normal position when said block indication relay responds to an indication code transmitted from the entrance end of said stretch while the contacts of said block relay occupy their normal position, means effective provided the contacts of said block repeater relay are in their normal position for maintaining them in such position when the block indication relay responds to an indication code transmitted while the contacts of said block relay are in their operated position, and means operating through said code communication system for causing said system of circuits to maintain traffic in said stretch when the contacts of said block indication repeater relay are in their normal position and the contacts of said block indication relay are in the position which they occupy when the relay responds to an indication code transmitted from the entrance end of the stretch while the contacts of said block relay are in their operated position.

8. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and

23

controlled from said office through said code communication system to at times prepare said stretch for traffic in said given direction, a signal at the entrance end of said stretch governed by said system of circuits, a block relay at the entrance end of said stretch, means governed by said system of circuits for moving the block relay contacts from their operated to their normal position when said system of circuits prepares said stretch for traffic and for thereafter maintaining said relay contacts in their normal position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, means effective when the contacts of said detector section repeater relay are moved to their operated position and the contacts of said block relay occupy their normal position to maintain the contacts of said block relay in their normal position as long as the contacts of said detector section repeater relay occupy their operated position, a block indication relay at the office governed through said code communication system and having contacts which are moved to a normal or to an operated position in accordance with the position of the contacts of said block relay, a block repeater relay at the office having contacts which occupy an operated position when said stretch is not prepared for traffic, means for moving the contacts of said block repeater relay to a normal position when said block indication relay responds to an indication code transmitted from the entrance end of said stretch while the contacts of said block relay occupy their normal position, means effective provided the contacts of said block repeater relay are in their normal position for maintaining them in such position when the block indication relay responds to an indication code transmitted while the contacts of said block relay are in their operated position, and occupancy indicating means at said office governed by said block indication relay provided the contacts of said block indication repeater relay are in their normal position.

9. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from said office through said code communication system to at times prepare said stretch for traffic in said given direction, a signal at the entrance end of said stretch governed by said system of circuits, a block relay at the entrance end of said stretch, means governed by

24

said system of circuits for moving the block relay contacts from their operated to their normal position when said system of circuits prepares said stretch for traffic and for thereafter maintaining said relay contacts in their normal position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, means effective when the contacts of said detector section repeater relay are moved to their operated position and the contacts of said block relay occupy their normal position to maintain the contacts of said block relay in their normal position as long as the contacts of said detector section repeater relay occupy their operated position, a detector section indication relay at the office governed through said code communication system in accordance with the position of the contacts of said detector section repeater relay, a block indication relay at the office governed through said code communication system and having contacts which are moved to a normal or to an operated position in accordance with the position of the contacts of said block relay, a block repeater relay at the office having contacts which occupy an operated position when said stretch is not prepared for traffic, means for moving the contacts of said block repeater relay to a normal position when said block indication relay responds to an indication code transmitted from the entrance end of said stretch while the contacts of said block relay occupy their normal position, means effective provided the contacts of said block repeater relay are in their normal position for maintaining them in such position when the block indication relay responds to an indication code transmitted while the contacts of said block relay are in their operated position, occupancy indicating means at said office, means governed by said detector section indication relay for controlling said occupancy indicating means, and means governed by said block indication relay provided the contacts of said block indication repeater relay are in their normal position for also controlling said occupancy indicating means.

10. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from said office through said code communication system to at times prepare said stretch for traffic in said given direction, a signal

at the entrance end of said stretch governed by said system of circuits, a block relay at the entrance end of said stretch, means governed by said system of circuits for moving the block relay contacts from their operated to their normal position when said system of circuits prepares said stretch for traffic and for thereafter maintaining said relay contacts in their normal position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, an auxiliary relay at said office having contacts which occupy a normal position when said stretch is not prepared for traffic, means governed through said code communication system by said detector section repeater relay and by said block relay in response to operation of said system of circuits to prepare said stretch for traffic in said given direction for moving the contacts of said auxiliary relay to their operated position and for thereafter maintaining them in such position during occupancy of the stretch, and occupancy indication means at said office governed by said block relay through said code communication system provided the contacts of said auxiliary relay are in their operated position.

11. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from said office through said code communication system to at times prepare said stretch for traffic in said given direction, a signal at the entrance end of said stretch governed by said system of circuits, a block relay at the entrance end of said stretch, means governed by said system of circuits for moving the block relay contacts from their operated to their normal position when said system of circuits prepares said stretch for traffic and for thereafter maintaining said relay contacts in their normal position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, a block indication relay at said office governed by said block relay through said code communication system,

a block indication repeater relay at said office having contacts which occupy an operated position when said stretch is not prepared for traffic, means governed through said code communication system by said detector section repeater relay and by said block relay in response to operation of said system of circuits to prepare said stretch for traffic in said given direction for moving the contacts of said block indication repeater relay to their normal position and for thereafter maintaining them in such position during occupancy of the stretch, and occupancy indication means at said office governed by said block indication relay provided the contacts of said block indication repeater relay are in their normal position.

12. In a system of centralized traffic control for a stretch of track through which traffic may move in a given direction and equipped with a code type communication system connecting the ends of said stretch with a control office, said code communication system including at the entrance end of the stretch a starting relay having contacts which are moved from a normal to an operated position in response to a change in apparatus conditions at said location and are restored to their normal position in response to transmission of an indication code from that location to the office, in combination, a detector track section at the entrance end of said track stretch, said detector track section having a track circuit including a track relay, a system of circuits extending the length of said stretch and governed by traffic conditions in said stretch and controlled from said office through said code communication system to at times prepare said stretch for traffic in said given direction, a signal at the entrance end of said stretch governed by said system of circuits, a block relay at the entrance end of said stretch, means governed by said system of circuits for moving the block relay contacts from their operated to their normal position when said system of circuits prepares said stretch for traffic and for thereafter maintaining said relay contacts in their operated position provided said stretch is vacant, a detector section repeater relay, means for said detector section repeater relay for causing its contacts to move from a normal to an operated position when the associated track relay releases, means for said detector section repeater relay for causing its contacts to move from their operated to their normal position when and only when the associated track relay is picked up and the contacts of the associated starting relay are in their normal position, a block indication relay at said office governed by said block relay through said code communication system, a block indication repeater relay at said office having contacts which occupy an operated position when said stretch is not prepared for traffic, means governed through said code communication system by said detector section repeater relay and by said block relay for moving the contacts of said block indication repeater relay to their normal position in response to operation of said system of circuits to prepare said stretch for traffic in said given direction and for thereafter maintaining them in such position during occupancy of the stretch, and means governed by said block indication relay through said code communication system provided the contacts of said block indication repeater relay are in their operated position for causing said system of circuits to maintain traffic in said stretch.

for a stretch of single track railroad connected at the ends by track switches with adjacent passing sidings and equipped with a code type communication system connecting the ends of said stretch with a control office, said code communication system including at each end of the stretch a starting relay having contacts which are moved from a normal to an operated position in response to a change in apparatus conditions at that location and are restored to their normal position in response to transmission of an indication code from that location to the office, in combination, a detector track section at each end of the stretch including the associated track switch and provided with a track circuit including a track relay, a system of reversible circuits extending the length of said stretch and governed jointly by traffic relays at opposite ends of the stretch so that at times the stretch is conditioned for traffic movements in one direction and at other times for traffic movements in the other direction, a signal at each end of the stretch for governing traffic movements into the stretch, means for controlling each signal in accordance with the condition of said system of circuits, manually controlled electroresponsive means at said office for designating the direction of traffic movements in said stretch and controlling the transmission of control codes by said code communication system by which said traffic relays are operated to cause said system of reversible circuits to condition the stretch for one direction of traffic or the other, each detector section track relay having associated therewith a detector section repeater relay, means for each detector section repeater relay for causing its contacts to move from a normal to an operated position when the associated track relay releases, means for each detector section repeater relay for causing its contacts to move from their operated to their normal position when and only when the associated track relay is picked up and the contacts

of the associated starting relay are in their normal position, a block relay at each end of the stretch, means at each end of the stretch effective when the portion of said system of reversible circuits for the portion of the stretch adjacent said end of the stretch prepares said stretch for traffic and indicates that such portion of the stretch is unoccupied for moving the contacts of the associated block relay from their operated to their normal position, means for each block relay effective on movement of the contacts of the associated detector section repeater relay to their operated position provided the contacts of said block relay are in their normal position and the associated traffic relay conditions that end of the stretch to be an entrance end for maintaining the contacts of said block relay in their normal position, an auxiliary relay at the office having contacts which occupy an operated position when said stretch is not prepared for traffic, means for moving the contacts of said auxiliary relay to a normal position when indication codes are transmitted from both ends of the stretch with the contacts of said block relays in their normal position, and means at said office governed by said block relays through said code communication system for controlling said electroresponsive traffic designating means provided the contacts of said auxiliary relay are in their normal position.
